UNITED STATES PATENT OFFICE.

HARVEY C. LOWRIE, OF DENVER, COLORADO.

PORTABLE WASH-STAND.

SPECIFICATION forming part of Letters Patent No. 358,743, dated March 1, 1887.

Application filed October 6, 1885. Serial No. 179,177. (No model.)

To all whom it may concern:

Be it known that I, HARVEY C. LOWRIE, of Denver, in the county of Arapahoe and State of Colorado, have invented certain new and useful Improvements in Portable Wash-Stands; and I do hereby declare that the following specification, taken in connection with the drawings furnished and forming a part of the same, is a clear, true, and complete description of the several features of my invention.

The prime objects of my said improvements are to provide in a portable wash-stand having a water-tank and a waste-tank for absolute security against overflow and leakage of the waste waters; also, for convenience in drawing off the latter and cleansing the waste-tank, and for filling the water-tank and cleansing it when required. For accomplishing these ends, I have, as I believe for the first time, combined with a bowl permanently set in a portable stand or cabinet a waste-tank which, although tightly coupled to the bowl, is readily detachable therefrom for convenience in cleansing, and from which, while still coupled, its contents can be drawn off. I have also provided for controlling all drip-water which can possibly escape from the coupling-joint, and I have so combined the bowl-coupling, the waste-tank, and a door of the cabinet that said door, when closed, serves as a tightening medium for the joint or coupling. With my water-tank I employ a pump, and these are so combined with each other and the top of the stand that, although the pump can be conveniently detached, and the water-tank wholly removed for cleansing, if need be, the latter is rendered accessible for that purpose without removing the pump, and said tank may at any time be conveniently supplied with water without moving the tank. I have also so organized and arranged the several parts of the apparatus within the cabinet as to economize in space and afford ample storage-room for the reception of various chamber utensils.

After a detailed description of the drawings, the several features deemed novel will be specified in the several clauses of claim hereunto annexed.

Figure 1 is a front view of a cabinet wash-stand embodying my several improvements in their best form, the doors being open for dis-

closing the interior. Fig. 2 is a plan view of the same, but with the top removed. Fig. 3 is an enlarged longitudinal vertical section of the same on the irregular dotted lines indicated in Fig. 2. Fig. 4 is a central longitudinal vertical section of the waste-tank. Fig. 5 is a horizontal section of the couplings between the bowl and tank on line *x*, Fig. 3, and it also shows the waste-tank, an adjacent part of one of the cabinet-doors, and a part of an interior partition in section. Fig. 6 is a vertical central section of the coupling-joint on line *y*, Fig. 5. Fig. 7, in vertical central section, illustrates a cabinet wash-stand embodying certain portions of my invention, but arranged to afford a specially prompt bowl-discharge, which is controlled by a treadle.

The cabinet *A* of the wash-stand illustrated in Figs. 1 to 3, inclusive, may be widely varied in construction, so far as relates to exterior finish, without departure from my invention, and the same is true of the interior, provided there be a suitable supporting-shelf, *a*, for the permanently-set bowl *B* and a suitable support, *b*, for the water-tank *C*, although said tank may be deeper and supported by the floor of the cabinet, if desired, and supports *c* and *c'* for the waste-tank *D*. At certain other points in the interior the cabinet must be constructed with reference to certain special purposes, as will be hereinafter indicated.

The top *E* of the stand is preferably composed of marble or of slate or metal marbleized; but it may be of wood, if desired. The doors *d* *d'* are preferably as shown.

The set bowl *B* is provided with a waste-pipe, *e*, which is in the form of a horizontal elbow, projecting at its outer end toward the front of the cabinet, and said end is tapered to form a nozzle, as clearly indicated at *e'* in Figs. 5 and 6. This elbow must, at its rear side, be firmly braced against horizontal thrusting-strains applied from the front side of the cabinet, and this is preferably provided for by bracing it with the adjacent interior wood-work of the cabinet, said elbow in this case passing through an opening in a vertical partition, *f*, and abutting against the side *f'* of said opening at the rear, as clearly indicated in Fig. 5.

The waste-tank *D*, in its best form, is com-

posed of sheet metal, and is rectangular in horizontal outline, is deeper at the front end than at the rear, and its bottom is rounded from side to side, as clearly shown. It is 5 mounted in place by means of two slide-flanges, g , at its top and sides, which occupy grooves or bearings g' in the wood-work of the cabinet and enable the tank to be easily run in and out longitudinally. At one side of this 10 tank and near its front end it is provided with a horizontal elbow, h , pointing rearward and having a socket, h' , to which the nozzle e of the bowl pipe or elbow e' is nicely fitted with or without suitable packing. The elbow h at the base 15 of its nozzle has a flange or shoulder, e'' , and the elbow h has outside of its socket a spring-catch, h^2 , so that when the waste-tank is pushed inward on its slide-bearings the socket registers with the nozzle, and said catch automatically locks them together, and when the 20 tank is to be removed said catch must first be depressed. A handle is located at the front end of the tank, as clearly shown. For as-suredly causing the socket and coupling to 25 maintain proper relations, the door d of the cabinet on its inner side and in the same horizontal plane is provided with a cushioned abutment, d' , which, when said door is closed, so engages with the front side of the tank-elbow h as to force it toward the bowl-elbow e ; and for maintaining pressure thereon a hook, d^2 , on the shelf a is engaged with a staple or screw-eye, d^4 , as shown in Fig. 1, or by means 30 of a turn-button and knob, d^5 , engaging with a keeper, d^6 , in the partition f , as clearly indicated in Fig. 5, either of these two forms of clamping devices being well suited for this 35 purpose. It will be seen that the door cannot be closed until the coupling has first been 40 properly connected.

I am aware that wash-bowls have heretofore been provided with flexible tubes serving as spouts for conveying water from said bowls into waste-tanks, and also provided with com-45 pressing devices, by which said tubes could be pinched together for retaining water in the bowls; but it will be obvious that such flexible tubes could only serve my purposes by employing therewith couplings substantially as shown, 50 by which they could be actually connected to and readily disconnected from the waste-tank, because, in order to positively guard against undue accumulations in the waste-tank, the water in the latter must be capable of back-55 ing up into the bowl, which would be impossible with a flexible pipe leading from a bowl and merely overhanging the waste-tank, as heretofore employed.

The importance of well guarding against 60 overflows and leakages will be obvious. For controlling all possible leakage at the elbow-coupling I have provided the socket h' with an interior annular drip-chamber, h^3 , as shown in Fig. 6, and this communicates with a con-65 ductor, i , which extends downward and beneath the waste-tank to its front end, and beneath this is a suitable slop-bucket, E . This

drip-conductor will serve a good purpose if it be no more than a solid wire or rattan; but I prefer it to be a pipe, as shown.

For convenience in drawing off the contents of the waste-tank into the bucket I have provided a discharge-opening guarded by an automatically-closed spindle-valve, F , forced to its seat by a spring and lifted by means of the 75 top of the spindle k , near the front end of the tank. It will be seen that as soon as the level of the water in said tank is on a line with the bottom of the bowl that fact will be promptly made apparent by the presence of water in the 80 bowl; but, as this might not be discovered until the bowl was again filled, I have provided an overflow-waste by way of the interior of the spindle k , which is tubular and has an entrance at k' on the overflow-line, thus causing 85 the overflow to fall into the bucket and, by the noise due to its fall, indicate the necessity for prompt attention.

In some cases, as a special precaution, the waste-tank is confined in position by means of 90 a spring-latch, h^4 , located on an interior partition and arranged to overlap the front end of the waste-tank near its upper end.

The water-tank C , as beforestated, is mounted on the shelf b , which is in slide-bearings, so 95 that it can be taken out and put in longitudinally, and thus enable the tank when empty to be dropped from its position and replaced; or said shelf may be left intact and the tank sufficiently pulled forward thereon by means 100 of its handle to enable it to be tilted downward at its front end, and thus afford ample access for cleansing it or for filling it, and without tilting.

The pump G may be widely varied; but this 105 has ball-valves which are simple, durable, and effective, and a nozzle, l , which overhangs the bowl, and it is operated by a rod extending through the marble top of the cabinet and provided with a handle or knob, l' .

For obtaining the best results I mount the pump so that it will rigidly depend from the marble top and be wholly detached from the water-tank. As here shown, there is near the top of the pump-barrel a flange, l^2 , which abuts 115 against the under side of the slab or top, and the top of the barrel is screw-threaded, so that it may be engaged by the internal thread of the cup-shaped escutcheon-plate l^3 , and thus be firmly clamped to the slab. The pump-rod 120 passes through a hole in said plate, which serves as a guide, and the knob l' is screwed upon said rod, thus enabling the pump to be lifted from the tank on removing the knob and plate and then lifting and laterally moving the top; or, by lifting said top bodily, the pump may be removed from the tank without separating it from said top.

When the water-tank and pump are arranged so as to permit the tank to be moved longitudinally and then tilted, the bottom of the pump should be considerably above the bottom of the tank; but when said tank is to be limited to movements in a vertical direction the pump

may be in contact with the bottom of the tank, although it should be sufficiently high to prevent the lifting of sediment and be practically a suspended pump.

5 The water-tank may be supplied from a nozzled bucket by way of a suitable opening in the front side of the tank at its top, or by way of an opening in the slab or top, as at *m*, and in this latter case a funnel can be used or a 10 pitcher relied upon, and said hole is preferably occupied by a close-bottomed soap-dish, which is fitted to said hole so that it will serve as a suitable cover.

The bowl in the stand thus far described is 15 provided with the usual waste-plug and a discharge-opening of the usual size, and I will next describe a cabinet having a larger waste-plug, which is controllable by a treadle.

Referring to Fig. 7, it will be understood 20 that the cabinet is mainly as before described, and differs therefrom internally only so far as is incidental to the variations in construction and arrangement of the bowl *B*, water-tank *C*, and waste-tank *D*. The pump *G* is substantially as before described. The wash-bowl *B* differs from the first in having an annular 25 waste-chamber, *B'*, and a large waste-plug, which is operated by a spring-spindle and a treadle, substantially as shown, described, and 30 claimed in my application for Letters Patent filed July 23, 1884, Serial No. 138,559. As a novel feature, however, said waste-chamber has a horizontal waste-pipe, *e*, which at its outer end is screw-threaded externally for receiving an internally-threaded sleeve, *e'*, having 35 at its outer end a tapered nozzle, *e'*, and also having arms by which it can be readily rotated. The waste-tank *D* in this cabinet is mounted upon a ledge, *n*, on the inner side of 40 the adjacent end of the cabinet, and also upon one or more opposite swinging brackets, *n'*, so that one side of said tank will be in close engagement with the interior of the end of the cabinet. On the opposite side of said tank 45 there is a socketed opening, *o*, to which the tapered nozzle *e'* is fitted, thus enabling the sleeve-nut, when rotated, to couple tightly and form a reliable connection between the bowl-chamber and the tank, suitable packing being 50 inserted at *p* to secure tight joints. In the event of possible leakage at this coupling, a drip-pan, *q*, is secured to the side of the tank, which discharges by way of its pipe *q'* into the slop-bucket *E'*. In this case the waste-tank 55 has an ordinary cock, *r*, for controlling the discharge, and it also has a cover, *s*, which is so tight and is at such a height above the bottom of the bowl as to afford but little liability to overflow, and ample vent will be afforded

while drawing off the water by lifting the plug *6c* of the basin. If desired, however, the cover may be made to fit loosely without fear of overflow.

In some classes of wash-stands I propose to dispense with the water-tank and pump, so 65 that they may be used with pitchers or with an elevated tank or with faucets communicating with water-service pipes, thus securing the conveniences of water-service without the danger of sewer-gas common to ordinary set bowls. 70 In still another variety I propose to employ only the bowl, the water-tank, and the pump, relying upon a slop-bucket for receiving the waste.

Having thus described my invention, I claim 75 as new and desire to secure by Letters Patent—

1. In a wash-stand, the combination of a set wash-bowl, a detachable waste-tank, and a waste-pipe provided with a readily-detachable coupling tightly connecting said tank with the 80 bowl, substantially as described, whereby the undue filling of the waste-tank will be promptly indicated by non-flowage from the bowl.

2. In a wash-stand, the combination of a set bowl, a detachable waste-tank, a socketed 85 coupling, and a drip-chamber provided with a conductor leading beneath the waste-tank, substantially as described.

3. In a wash-stand, the combination of a set bowl, a detachable waste-tank, a socketed 90 coupling for connecting said bowl and tank, and a spring-latch for locking the coupling-joint, substantially as described.

4. In a wash-stand, the combination, with a set bowl and a sliding detachable waste-tank, 95 of a socketed coupling between said tank and bowl, and a hinged door on said stand provided with an abutment for forcing and holding the parts of said coupling together on closing said door, substantially as described. 100

5. In a portable wash-stand, the combination of a set bowl, a detachable water-tank, and a pump secured to the wash-stand top extending within said tank and communicating with said bowl, substantially as described, 105 whereby either the pump or the tank may be separately removed for repairs or for cleansing and without disturbing the bowl.

6. In a portable wash-stand, the combination of a pendent pump and a sliding water-tank, substantially as described, whereby, without disturbing the pump, the tank may be moved longitudinally and tilted. 110

HARVEY C. LOWRIE.
